(57) **ABSTRACT**

A new and distinct cultivar of Poinsettia plant named 'Bkponai', characterized by its broadly upright and uniformly mounding plant habit; moderately vigorous growth habit; freely branching habit; dark green-colored leaves; large and full inflorescences with bright red-colored flower bracts and numerous cyathia; and excellent post-production longevity.

2 Drawing Sheets

1

Botanical designation: *Euphorbia pulcherrima* Willd.
Cultivar denomination: 'BKPONAI'.

BACKGROUND OF THE INVENTION

The present invention relates to a new and distinct cultivar of Poinsettia plant, botanically known as *Euphorbia pulcherrima* Willd. and hereinafter referred to by the name 'Bkponai'.

The new Poinsettia plant is a product of a planned breeding program conducted by the Inventor in De Kwakel and Maasdijk, The Netherlands. The objective of the breeding program is to create new uniform and freely-branching Poinsettia plants with good postproduction longevity.

The new Poinsettia plant originated from a cross-pollination made by the Inventor in January, 2009 in De Kwakel, The Netherlands of a proprietary selection of *Euphorbia pulcherrima* Willd. identified as code number 2000417, not patented, as the female, or seed, parent with a proprietary selection of *Euphorbia pulcherrima* Willd. identified as code number 2000430, not patented, as the male, or pollen, parent. The new Poinsettia plant was discovered and selected by the Inventor as a single flowering plant within the progeny of the stated cross-pollination in a controlled greenhouse environment in Maasdijk, The Netherlands in December, 2011.

Asexual reproduction of the new Poinsettia plant by terminal vegetative cuttings in a controlled greenhouse environment in Maasdijk, The Netherlands since March, 2012 has shown that the unique features of this new Poinsettia plant are stable and reproduced true to type in successive generations of asexual reproduction.

SUMMARY OF THE INVENTION

Plants of the new Poinsettia have not been observed under all possible combinations of environmental conditions and cultural practices. The phenotype may vary somewhat with

2

variations in environmental conditions such as temperature, daylength and light intensity, without, however, any variation in genotype.

The following traits have been repeatedly observed and are determined to be the unique characteristics of 'Bkponai'. These characteristics in combination distinguish 'Bkponai' as a new and distinct Poinsettia plant:

1. Broadly upright and uniformly mounding plant habit.
2. Moderately vigorous growth habit.
3. Freely branching habit.
4. Dark green-colored leaves.
5. Large and full inflorescences with bright red-colored flower bracts and numerous cyathia.
6. Excellent post-production longevity.

Plants of the new Poinsettia can be compared to plants of the female parent selection. Plants of the new Poinsettia differ primarily from plants of the female parent selection in the following characteristics:

1. Plants of the new Poinsettia are more upright than and not as broad as plants of the female parent selection.
2. Plants of the new Poinsettia have darker green-colored leaves than plants of the female parent selection.
3. Plants of the new Poinsettia and the female parent selection differ in flower bract color as flower bracts of the female parent selection are orange red in color.

Plants of the new Poinsettia can be compared to plants of the male parent selection. Plants of the new Poinsettia differ primarily from plants of the male parent selection in the following characteristics:

1. Plants of the new Poinsettia are more upright than and not as broad as plants of the male parent selection.
2. Plants of the new Poinsettia have lighter green-colored leaves than plants of the male parent selection.
3. Plants of the new Poinsettia and the male parent selection differ in flower bract color as flower bracts of the male parent selection are pink in color.

Plants of the new Poinsettia can be compared to plants of *Euphorbia pulcherrima* Willd. 'Floasatur', disclosed in U.S. Plant Pat. No. 20,230. In side-by-side comparisons, plants of

the new Poinsettia differ primarily from plants of 'Floasatur' in the following characteristics:

1. Plants of the new Poinsettia are more freely branching than plants of 'Floasatur'.
2. Plants of the new Poinsettia flower earlier than plants of 'Floasatur'.⁵
3. Flower bracts of plants of the new Poinsettia are more rugose than flower bracts of 'Floasatur'.

BRIEF DESCRIPTION OF THE PHOTOGRAPHS 10

The accompanying photographs illustrate the overall appearance of the new Poinsettia plant showing the colors as true as it is reasonably possible to obtain in colored reproductions of this type. Colors in the photographs may differ slightly from the color values cited in the detailed botanical description which accurately describe the colors of the new Poinsettia plant.¹⁵

The photograph on the first sheet comprises a side perspective view of a typical flowering plant of 'Bkponai'²⁰ grown in a container.

The photograph on the second sheet is a close-up view of a typical flowering plant of 'Bkponai'.

DETAILED BOTANICAL DESCRIPTION 25

The aforementioned photographs and following observations and measurements describe plants grown during the summer and late autumn in 10-cm containers in a glass-covered greenhouse in De Lier, The Netherlands and under cultural practices typical of commercial Poinsettia production. During the production of the plants, day temperatures ranged from 17° C. to 18° C. and night temperatures ranged from 15° C. to 16° C. Plants were pinched one time and were 22 weeks old when the photographs and the detailed description were taken. In the following description, color references are made to The Royal Horticultural Society Colour Chart, 2015 Edition, except where general terms of ordinary dictionary significance are used.³⁰

Botanical classification: *Euphorbia pulcherrima* Willd. 'Bkponai'.⁴⁰

Parentage:

Female, or seed, parent.—Proprietary selection of *Euphorbia pulcherrima* Willd. identified as code number 2000417, not patented.

Male, or pollen, parent.—Proprietary selection of *Euphorbia pulcherrima* Willd. identified as code number 2000430, not patented.⁴⁵

Propagation:

Type.—Terminal vegetative cuttings.

Time to initiate roots, summer and winter.—About 18 days at temperatures about 19° C. to 21° C.

Time to produce a rooted young plant, summer.—About three weeks at temperatures about 17° C. to 19° C.⁵⁰

Time to produce a rooted young plant, winter.—About four weeks at temperatures about 17° C. to 19° C.

Root description.—Medium in thickness, fibrous; typically white in color, actual color of the roots is dependent on substrate composition, water quality, fertilizer type and formulation, substrate temperature and physiological age of roots.⁶⁰

Rooting habit.—Freely branching; dense.

Plant description:

Plant and growth habit.—Broadly upright and uniformly mounded plant habit; inverted triangle with

rounded crown; large full inflorescences positioned above the foliar plane; moderately vigorous growth habit and moderate growth rate.

Plant height, soil level to top of foliar plane.—About 18.9 cm.

Plant height, soil level to top of floral plane.—About 21.1 cm.

Plant diameter or spread.—About 32.6 cm.

Lateral branch description.—Branching habit: Freely branching habit, about six lateral branches develop after pinching. Length: About 12.8 cm. Diameter: About 6 mm. Internode length: About 7 mm. Strength: Moderately strong. Texture and luster: Smooth, glabrous; glossy. Angle: About 40° from vertical. Color, when developing: Close to 146C; at the internodes, close to 144B. Color, developed: Close to between 146B and 147B, tinged with close to 177A and 177B.

Leaf description.—Arrangement: Alternate, simple. Length: About 10.3 cm. Width: About 7.3 cm. Shape: Ovate to roughly deltoid. Apex: Apiculate. Base: Obtuse. Margin: Entire; occasionally with a single shallow lobe. Venation pattern: Pinnate. Texture and luster, upper surface: Slightly rugose, glabrous; moderately glossy. Texture and luster, lower surface: Slightly rugose, glabrous; matte. Color: Developing leaves, upper surface: Close to between 137A and 141A. Developing leaves, lower surface: Close to 138A. Fully expanded leaves, upper surface: Darker than between 139A and N189A; venation, close to 175A and 175B. Fully expanded leaves, lower surface: Close to NN137D; venation, close to 176B to 176C. Petioles: Length: About 4.1 cm. Diameter: About 3 mm. Strength: Moderately strong. Texture and luster, upper and lower surfaces: Smooth, glabrous; glossy. Color, upper surface: Close to 187A to 187B. Color, lower surface: Close to 183A to 183B.

Inflorescence description:

Inflorescence type and habit.—Large full inflorescences are compound corymbs of cyathia with bright red-colored flower bracts subtending the cyathia; one inflorescence per lateral branch with inflorescences positioned above and beyond the foliar plane.

Fragrance.—None detected.

Natural flowering season.—Plants flower naturally during the late autumn to winter under long nycto-period conditions; inflorescence initiation and development can be induced under artificial long nycto-period conditions; response time is about 70 days.

Post-production longevity.—Excellent post-production longevity; plants of the new Poinsettia maintain good substance and bract color for about 30 days; flower bracts not persistent.

Inflorescence width.—About 19.4 cm.

Inflorescence height.—About 8.5 cm.

Flower bracts.—Quantity per inflorescence: About twelve. Length: About 9.8 cm. Width: About 7.4 cm. Shape: Ovate. Apex: Apiculate. Base: Broadly acute to obtuse. Margin: Entire to very slightly repand. Aspect: Slightly upright to horizontal. Venation: Pinnate. Texture and luster, upper and lower surfaces: Slightly rugose, glabrous; matte. Color: Developing bracts, upper surface: Close to 46B. Developing bracts, lower surface: Close to 46C. Fully expanded bracts, upper surface: Close to N45B; venation, close

to N45B; color does not fade with development. Fully expanded bracts, lower surface: Close to N45C; venation, close to N45C; color does not fade with development. Bract petioles: Length: About 1.9 cm. Diameter: About 2.5 mm. Texture and luster, 5 upper and lower surfaces: Smooth, glabrous; glossy. Color, upper surface: Close to 187B. Color, lower surface: Close to 185A.

Cyathia.—Quantity per corymb: About eight. Length: About 1.3 cm. Width: About 6.5 mm. Shape: Ovoid. 10 Texture and luster, inner and outer surfaces: Smooth, glabrous; matte. Color, developing, inner surface: Close to N144B; towards the apex, close to 152C. Color, developing, outer surface: Close to 144C; towards the apex, close to 145A and 53A. Color, fully developed, inner surface: Close to 144C; towards the apex, close to 183B. Color, fully developed, outer surface: Close to 143A and 143B; towards the apex, close to 45A. Nectaries: Quantity per cyathium: Typically two. Length: About 3 mm. 15 Diameter: About 3 mm. Shape: Club-shaped. Texture and luster, inner and outer surfaces: Smooth, glabrous; matte. Color, developing, inner and outer surfaces: Close to 145B. Color, fully developed, inner and outer surfaces: Close to 151C to 151D. 20

25

Pedicels.—Length: About 3 mm to 4 mm. Diameter: About 2.5 mm. Strength: Moderately strong. Aspect: Erect to about 30° from vertical. Texture and luster: Smooth, glabrous; glossy. Color: Close to 144C.

Reproductive organs.—Stamens: Quantity per cyathium: About 20. Filament length: About 3 mm. Filament color: Close to 47A. Anther shape: Club-shaped. Anther length: About 1 mm. Anther color: Close to 183A to 183B. Amount of pollen: Moderate. Pollen color: Close to 14A to 14B. Pistils: Pistil development has not been observed on plants of the new Poinsettia. Seeds and fruits: Seed and fruit production has not been observed on plants of the new Poinsettia.

15 Pathogen & pest resistance: Plants of the new Poinsettia have not been shown to be resistant to pathogens and pests common to Poinsettia plants.

Temperature tolerance: Plants of the new Poinsettia have been observed to tolerate high temperature about 35° C. and to be suitable for USDA Hardiness Zones 10 to 12. 20

It is claimed:

1. A new and distinct Poinsettia plant named 'Bkponai' as illustrated and described.
